UNITED STATES PATENT OFFICE

LAURENCE L. BUCHANAN, OF INDEPENDENCE, AND EDWARD M. BOHLKEN, OF KANSAS CITY, MISSOURI

PRINTING MACHINE

Application filed October 11, 1928. Serial No. 311,784.

Our invention relates to printing presses and while originally designed for printing the names of colors on cans containing paint, it may be employed to advantage for printing any desired information on cans or various other cylindrical objects.

In carrying out our invention we employ a reciprocatory slide for carrying the cans past suitable printing means such as type, symbols, etc., which print the desired information upon said cans. Said slide also carries an ink roller which keeps the type well coated with ink so that the printing applied to the cans or labels thereon will be clear and distinct.

Provision is also made for distributing the ink uniformly upon the ink roller and for handling cans and other cylindrical articles of different sizes, and in order that the invention may be fully understood reference will now be had to the accompanying drawings, in which:

Fig. 1 is a plan view of the printing press. Fig. 2 is a broken longitudinal section of 25 the press on line 2—2 of Fig. 1.

Fig. 3 is a broken vertical cross section of the press on line 3—3 of Fig. 2.

Fig. 4 is an enlarged vertical section of the ink roller and its supporting means.

Fig. 5 is an enlarged fragmentary vertical section on line 5—5 of Fig. 1, showing the printing means and an adjustable support therefor.

Fig. 6 is a broken cross section on line 6—6 of Fig. 1, of a rotatable carrier for the cans or other cylindrical articles to be printed upon.

Fig. 7 is a section on line 7 of Fig. 3, showing ratchet mechanism employed in carrying out the invention.

Referring in detail to the different parts, 2 designates a suitable support or table consisting of a top 4, legs 6 and braces 8. The top 4 has a longitudinal opening 10 and slideways 45 12 disposed at opposite sides of said opening 10. 14 designates a reciprocatory slide or carriage mounted in the slideways 12 and arranged to be moved automatically in one direction by means of a counterweight 16 and a cable 18, and manually moved in the oppo-

site direction by means of a foot treadle 20, a connecting rod 22, a lever 24 and a cable 26.

The counterweight 16 operates in a vertical guide 28 at one end of the table 2 while the cable 18 runs over a sheave 30 and is attached at its lower end to the counterweight 16 and at its upper end to an eye 32 threaded into the reciprocatory carriage 14. The treadle 20 and the lever 24 are operably united by the connecting rod 22 and mounted at 55 one end upon pivots 34 and 36, respectively. The cable 26 runs over a sheave 38 and is attached at its opposite ends to the lever 24 and an eye 40, which latter is threaded into the carriage 14.

42 designates a rotatable carrier for conveying the cans or other cylindrical articles B past the printing mechanism hereinafter described in detail. Said carrier 42 consists of a horizontally disposed member provided with a fixedly mounted gear wheel 44 and having a circular recess 46 in its upper portion for the reception of the lower ends of the cylindrical articles which are firmly held, one at a time, in said recess 46 by suitable means such as a spring pressed detent 48.

The rotatable carrier 42 is fixedly mounted upon stub shaft 50 having a reduced lower end 52 for entering any of the holes 54 in the reciprocatory carriage 14. Several rotatable carriers 42 of different diameters are provided for holding cans or other cylindrical articles of different sizes and as the gear wheel 44 of each carrier 42 must intermesh with a rack 56 it is necessary to locate the holes 54 different distances from said rack 56, as shown by Fig. 1. The rack 56 is secured to the upper inner side of one of the slideways 12 by suitable means such as screws 58.

60 designates a vertically disposed ink roller mounted upon a shaft 62 journaled at its ends in plates 64 and 66 secured to the upper and lower ends, respectively, of a yoke 68 which is pivotally mounted upon a bracket 70 secured to a post 72 fixedly mounted upon the carriage 14 near one end of the latter. When the roller 60 becomes worn out it can be readily replaced by another by taking off 100

the plate 64 which is held upon the yoke 68 by suitable means such as a screw 74.

76 designates an antifriction roller mounted between the plate 66 and the lower end of 5 the yoke 68. Said roller 76 is normally held against a guide rail 78 by means of a coil spring 80 attached at its ends to the plate 66 and the post 72 and prevents the ink roller 60 from moving too close to said guide 10 rail 78.

The spring 80 also holds the ink roller 60 against a vertically disposed ink distributing disk 82 mounted upon a stub shaft 83 journaled in a bearing 84 secured on top of the 15 adjacent slideway 12. The stub shaft 83 is provided with a fixedly mounted ratchet wheel 88 which is rotated step by step by a ratchet lever 90 extending downwardly through a slot 92 in the table top 4 and connected to one end of a retractile spring 94 which is attached at its opposite end to an 20 eye 96. The lever 90 is arranged in the path of an arm 98 depending from the carriage 14 so that as the latter approaches the end of its 25 movement to the left, Fig. 2, said arm 98 will contact with and push the lever 90 backwardly, causing it, through the ratchet mechanism, to rotate the disk 82 one step.

100 designates a clamp for holding suitable printing means such as type A in the path of the ink roller 60. Said clamp 100 is mounted upon an arm 102 adjustably mounted upon a standard 104, which in turn is adjustably mounted in a bracket 105 secured 30 by suitable means such as bolts 108 to the adjacent side of the table 2. The type A is removably held in the clamp 100 by means of a stationary jaw 109 and a removable jaw 110, which latter is held in position against the 35 type by set screws 112. The arm 102 has a longitudinal slot 114 so that it may be adjusted backward or forward upon the standard 104 to bring the face of the type A in line with the cylindrical articles to be printed 40 upon, and after such adjustment said arm 102 is clamped against shoulders 116 upon the standard 104 by means of a plate 118 and a set screw 120, which latter is threaded upon a stud 122 projecting from the top of the 45 standard 104. The bracket 105 has a plate 106 removably held in position by screws 124. By loosening said screws 124 the standard 104 may be adjusted vertically to position the type A at the desired elevation for printing 50 upon the cans or other cylindrical articles.

In practice the ink distributing disk 82 is coated with ink and a can or other cylindrical article B is placed in upright position 55 in the recess 46 of the rotatable carrier 42 where it is firmly held by the spring pressed detent 48. The treadle 20 is then depressed to effect the movement of the reciprocatory carriage 14 to the right, Fig. 2. 60 As the carriage 14 travels to the right the

gear wheel 44 is rotated by the rack 56 and in turn rotates the carrier 42 with the cylindrical article B which is printed upon as it rotates in contact with the type A. When the carriage 14 reaches the end of its movement to the right the cylindrical article B is removed from the rotatable carrier 42, after which the treadle 20 is relieved of sufficient pressure to permit the counterweight 16 to return the carriage 14 to its normal position 75 at the left of the table 2, whereupon another cylindrical article to be printed upon is placed in position upon the carrier 42. As the carriage 14 approaches the end of its movement to the left the arm 98 contacts 80 with the ratchet lever 90 and pushes the same backwardly against the action of the spring 94, thereby causing said ratchet lever 90 to turn the disk 82 one step through the intermediary of the ratchet wheel 88 and cause 85 said disk to distribute ink upon the roller 60 as it rotates in contact therewith.

From the foregoing description it is apparent that we have provided a printing press which is well adapted for the purpose 90 intended and while we have shown one form of the invention we reserve all rights to such other forms and modifications thereof as properly fall within the spirit and scope of the invention as claimed.

Having thus described our invention, what we claim and desire to secure by Letters Patent, is:

1. In a press of the character described, a suitable support, a reciprocatory member mounted upon said support, a horizontally disposed rotatable member mounted upon said reciprocatory member and having a recess in its upper portion for the reception of the lower end of an article to be printed 100 upon, coacting means on said support and said rotatable member for rotating the latter as it is carried to and fro on the reciprocatory member, and printing means arranged in the path of the article for printing 105 thereon.

2. In a press of the character described, a suitable support, a reciprocatory member mounted upon said support, a horizontally disposed rotatable member mounted upon 110 said reciprocatory member and having a recess in its upper portion for the reception of the lower end of an article to be printed upon, means carried by said rotatable member for holding the article in said recess, 115 coacting means on said support and said rotatable member for rotating the latter as it is carried to and fro on the reciprocatory member, and printing means arranged in the path of the article for printing thereon. 120

3. In a press of the character described, a suitable support, a reciprocatory member mounted upon said support, means on said reciprocatory member for carrying articles to be printed upon, printing means asso- 125 130

ciated with said support for printing said articles, clamp means for holding said printing means, a slotted arm for supporting said printing means, a standard upon which said slotted arm is adjustably mounted, and a bracket on the support in which said standard is adjustably mounted.

5 4. In a press of the character described a rotary carrier having a recess for the reception of an article to be printed upon, means on said carrier for holding said article in said recess, a gear fixed to said carrier for rotating the latter, a stationary rack with which said gear intermeshes, and reciprocatory means for moving said carrier back and forth.

10 5. In a press of the character described a rotary carrier having a recess for the reception of an article to be printed upon, spring pressed means on said carrier for holding said article in said recess, a gear fixed to said carrier for rotating the latter, a stationary rack with which said gear intermeshes, reciprocatory means for moving said carrier back and forth, and printing means arranged in the path of said article for printing the latter.

15 In testimony whereof we affix our signatures.
